UNITED STATES PATENT OFFICE

ERNEST A. DE WOLF, OF CRANSTON, RHODE ISLAND, ASSIGNOR TO UNIVERSAL WINDING COMPANY, OF BOSTON, MASSACHUSETTS, A CORPORATION OF MASSACHUSETTS

COP HOLDER

Application filed April 11, 1928. Serial No. 269,166.

This invention relates to improvements in cop-holders for supporting cops, cones or packages of yarn, thread and other strand material to deliver the same for various purposes in the textile art.

A principal object of the invention is to provide a cop-holder for use on creels of the magazine type wherein a plurality of non-rotatable cops, cones or packages are arranged to deliver over their ends to supply the yarn to a warping or other machine.

Another object of the improvement is to provide a cop-holder of the type specified which normally holds the cop, cone or package non-rotatably, but which is so constituted as to permit manual rotation of the cop to facilitate the tying up of the ends from the different supplies.

Further objects of the improvement are set forth in the following specification which describes a preferred form of construction of the device, by way of example only, as illustrated in the accompanying drawings. In the drawings:

25 Fig. 1 is a general plan view showing the present improved cop-holder as applied to use on a magazine creel for holding a series of yarn cones arranged in pairs with the last end of the yarn from one cone spliced to the leading end of the yarn from a reserve cone to provide for continuous delivery from first one cone and then another;

Fig. 2 is an enlarged side view of the improved cop-holder showing a yarn cone in place thereon and illustrated in longitudinal sectional view; and

Fig. 3 is an end view of the cop-holder showing it partly in section on line 3-3 of Fig. 2.

40 My present improved cop-holder is adapted for use particularly with magazine creels of the type shown and described in my previous U. S. Letters Patent No. 1,660,299, granted February 21, 1928. In this type of creel the yarn cops or cones are arranged in pairs with the leading end of the yarn from one cop delivering through a suitable tension-device and the last end of the yarn on this cop spliced to the leading end from a reserve 45 cop so that when the first cop is exhausted the

yarn will deliver from the reserve cop. This arrangement provides that a fresh cop may be creelied in place of the exhausted one and its end spliced to the delivering cop so that a continuous delivery of the material is maintained without stoppages to doff the empty cop-tubes and supply fresh cops in their place. It will be understood that in winding cops or packages for this purpose a free length of 55 yarn is left in starting the winding to provide for tying or splicing it to the yarn on the reserve cop. This length of yarn is usually wound a few times around the base end of the cop-tube or carrier so that it may be conveniently unwound to tie it to the end of the 60 associated reserve cop.

Another object of the present improvement, therefore, is to provide means for securing the cop or package fixedly in place to normally support it non-rotatably on the holder, while adapting it to be rotated manually when desired so that the reserve end of 65 the yarn may be readily and conveniently unwound from the base of the cop-tube or carrier.

In Fig. 1 of the present drawings I have illustrated a plurality of yarn cops in the 70 form of cones C supported on cop-holders 2 which are carried by brackets or arms 3 swiveled on vertical rods or uprights 4. The rods or uprights 4 form the framework of the creel, and usually another set of uprights 5 75 is provided at the front of the frame for supporting tension-devices 6 of any usual construction. The tension-devices 6 as herein shown comprise brackets 7 carrying suitable pins 8 on which the tension-disks 9 are mounted. The yarns y from the cones C draw forward to the tension-devices 6, and passing through suitable guides 10, lead between the tension-disks 9 and around the pins 8 to forwardly disposed guides 11. The yarns draw 80

from the tension-device along the side of the creel to the point of take-up which may be a warping machine or any other apparatus as employed for balling or beaming a plurality of ends from the creel. The holders are adapted to swing back into the position illustrated in dotted lines in Fig. 1 to facilitate the doffing of the empty cop-tubes or carriers therefrom and placing of the fresh cops thereon.

10 The present improvement is concerned with the cop-holder proper which is adapted to be mounted on the end of the arm 3 in any suitable manner, and preferably by means 15 adjustable to permit the cops or cones to be set in proper relation with their axes directed toward the tension-devices 6. For this purpose I may employ a ball-and-socket joint between the cop-holder 2 and the arm 3 as illustrated in Fig. 2 of the drawings and herein- 20 after more particularly described.

The present type of cop-holder is particularly adapted for holding packages of tapered or conical form wound on hollow paste- 25 board tubes, as distinguished from the cop-holders shown in the prior patent above referred to for supporting cones wound on wooden cores or carriers. The paper cop-tubes are used more particularly on winding 30 machines for producing cross-wound cones of precision wind, for example in packaging materials such as silk, rayon and the like, and the present improved cop-holder is designed for use in supporting the cones on a creel of 35 any suitable type. It is to be understood, however, that it may be used for other purposes and in other embodiments as regards its form of construction and the method of its mounting.

40 In the present embodiment of the invention the cop-holder 2 is of skeleton structure having a plurality of longitudinal ribs or blades 14 connected together and supported from their ends. As herein shown there are three 45 of the ribs 14 equidistantly spaced concentrically of the axis of the holder and arranged in inclined relation to adapt them to be inserted into the larger or base end of the conical cop-tube *c*. At the base of the holder 2 50 the ribs 14 are joined to a central hub 15 having a spherical end 16 adapted to fit into the concaved cup or socket-bearing 17 at the end of the supporting arm 3. The hub 15 is formed with an axial opening, preferably of 55 rectangular shape, into which is inserted the squared end of a bolt 18 having a head abutting the end of the hub. The shank 20 of the bolt projects through an enlarged opening 21 in the cup or bearing 17 with a nut 22 60 screwed thereon to clamp the ball-end of the hub snugly against the bearing. By loosening the nut 22 the ball-and-socket bearing may be adjusted to vary the position of the cop-holder 2 on the arm 3 whereby its axis 65 can be alined with the tension-device. The

forward ends of the ribs 14 are rounded off and connected to a central hub 23.

The ribs 14 are formed with cross slots 24 located substantially midway between their ends to provide recessed seats for a ring or annulus 25. The ring 25 serves as the means for securing the top-tube *c* fixedly in place on the holder while adapting the cop to be manually rotated about its axis. The ring 25 may be formed of wire having its ends meeting in a closed joint, and preferably its periphery is scored or knurled to provide teeth or serrations for frictionally gripping the interior of the cop-tube *c*. The ring 25 fits loosely in the slots 24 so that it may be turned freely on the holder 2; and also to adapt it to adjust itself to fit the interior of the cop-tube as the latter rests on the edges of the ribs 14.

In applying the cop or cone *C* to the holder 2 it is only necessary to slide the cop-tube *c* along the ribs or blades 14 until the roughened periphery of the ring 25 engages frictionally with the interior of the tube at its larger end. That is to say, the tube is forced or crowded onto the ring 25 to cause the latter to bite into its interior to grip the tube to secure the cop in place as shown in Fig. 2 of the drawings. Normally, the weight of the cop will cause the cop-tube *c* to rest against the edges of the ribs 14 to center it on the holder and steady it in position with the ring 25 frictionally engaging the interior of the tube to hold it against longitudinal movement.

In the operation the cop or cone *C* is held in place with the interior of its cop-tube *c* engaging and resting on the edges of the ribs 14, there being sufficient frictional resistance between the ribs and the tube to normally hold the package from turning. In tying up the ends between the associated cops or packages 105 the operator first unwinds the length of reserve yarn *y'* from the end of the tube *c* of the delivering cone and this may be very conveniently accomplished by grasping the end of the cop-tube between the fingers and rotating the whole cone on the holder 2. When the tube is grasped in this manner its frictional contact with the ribs 14 may be overcome by manual pressure so that the tube may be turned with the ring 25 rotating with it. 110 After a sufficient length of the reserve yarn *y'* has been unwound by rotating or turning the tube with the fingers it is tied to the leading end of the next cone *C'* in the series which has been creel as a reserve supply. There 115 will be considerable slack in the spliced length of yarn joining the two cones and it has been found advisable to wind the slack onto the surface of the reserve cone as indicated at *x* in Fig. 1 of the drawings. This is accomplished by rotating the reserve cone *C'* on its holder and the present construction of the holder provides for this convenient method of operation. That is to say, the operator 120 may readily turn or rotate the reserve cone 125 130

on its axis until the yarn has been wound onto its surface to take up the slack.

In this way the ends of the yarn or thread may be conveniently spliced or tied together so that the material will deliver first from one cone and then from the next reserve cone in the series, and so on in succession without arresting the delivery to creel and tie up the fresh cones. It will be understood, of course, that after the yarn on the first cone has been exhausted and the delivery is continued from the reserve cone, the empty cop-tube is doffed from the holder and another reserve cone applied in its place. This is accomplished by swinging the cop-holder back into the position illustrated by dotted lines in Fig. 1, and after a fresh cone has been placed thereon it is moved back into operative position with the last end from the delivering cone connected to the leading end of the fresh cone. In this way the delivery is maintained continuous with new cones creel'd while the warping or other operation is being carried on.

It will be observed from the above that my invention provides a particularly simple and ingenious construction of the cop-holder to adapt it to support cops, cones or other packages of yarn, thread and strand material, with the package normally held non-rotatably to adapt the yarn to be delivered over its end; but with means provided for allowing the manual rotation of the cop-tube so that the reserve yarn may be conveniently and expeditiously unwound from its end to facilitate piecing it up or splicing it to the end from the reserve cone. It will be understood, of course, that the cone or package may be turned on its axis to unwind the reserve yarn without interfering with or interrupting the delivery of the material over the end of the cone as long as the operator does not grasp the outside of the cone itself.

While I have herein shown and described a preferred embodiment of the invention it is to be understood that various modifications may be made in the form and construction of its parts and in the method of applying it to use without departing from the spirit or scope of the invention. Therefore, without limiting myself in this respect, I claim:

1. In a holder for cops, cones and packages of strand material the combination of means adapted to be inserted within the interior of the package to support it therefrom and normally restrain it from turning thereon, and means rotatable on the cop-holder and adapted to frictionally engage the interior of the opening in the package to secure it in place longitudinally of the holder while permitting it to be manually turned on its axis for the purpose specified.

2. In a holder for cops, cones and packages of strand material the combination of means adapted for insertion into the interior of the

opening in the package to engage at a plurality of points spaced therearound, and means rotatable on the holder and projecting beyond the periphery thereof to adapt it to frictionally engage the interior of the opening to secure the package in place on the holder while permitting it to be manually turned thereon for the purpose specified. 70

3. A holder for cops, cones and packages of strand material comprising a member provided with longitudinal ribs adapted for insertion into the interior of the cop-tube, and an annulus encircling the ribs to adapt it to engage frictionally with the interior of the cop-tube and mounted free to rotate about the member to permit the cop-tube to be turned on its axis. 75

4. In a cop-holder of the type specified, the combination of a member provided with radially-projecting longitudinal ribs adapted for insertion into the interior of the cop-tube, and a ring encircling the ribs and rotatably mounted thereon to adapt it to frictionally grip the interior of the cop-tube to secure it in place on the holder while permitting the 90 cop to be turned on its axis. 90

5. In a device of the type specified, the combination of a cop-holder having a plurality of radially projecting longitudinal ribs adapted for insertion into the interior of the cop-tube and provided with slots in their peripheral edges, and a ring seated in said slots to adapt it to rotate on the axis of the holder. 95

6. In a device of the type specified, the combination of a holder comprising a plurality of longitudinal ribs disposed radially of its axis, and an annulus rotatably mounted on said holder surrounding the ribs and projecting beyond the periphery thereof. 100

7. A holder for cops, cones and packages of strand material comprising a central support with longitudinal ribs projecting radially therefrom, said ribs formed with slots in their peripheral edges, and a ring seated in said slots surrounding the ribs to adapt it to be rotatively held thereon. 110

8. A cop-holder for the purpose specified comprising a member formed with a hub at one end, ribs projecting radially therefrom and extending forwardly and joined together at their opposite ends, and an annulus encircling said ribs and rotatably mounted thereon. 115

In testimony whereof I hereunto affix my 120 signature.

ERNEST A. DE WOLF.
